UNITED STATES PATENT OFFICE

ROBERT E. STUBBS, OF DULUTH, MINNESOTA

DRILL-PRESS TABLE

Application filed May 10, 1927. Serial No. 190,216.

The present invention relates to improvements in drill press tables and has for its principal object to provide a work support which is capable of various adjustments whereby the work can be properly supported on the table while undergoing a drilling operation.

One of the important objects of the present invention is to provide a drill press table 10 wherein the same includes a table top which comprises a pair of complementary sections capable of being adjusted to provide a vice, the table top being arranged on a head for rotation thereon, said head being further 15 adapted for vertical swinging movement in order to tilt the table top to any desired angle.

A further object is to provide a drill press table of the above-mentioned character which is simple in construction, inexpensive, and 20 furthermore adapted to the purposes for which the same is designed.

Other objects and advantages of this invention will become apparent during the course of the following description.

25 In the accompanying drawing forming part of this specification and in which like numerals are employed to designate like parts throughout the same:

Figure 1 is a side elevation of the drill 30 press table embodying my invention.

Figure 2 is a similar view taken at right angles thereto.

Figure 3 is a vertical sectional view taken substantially on the line 3—3 of Figure 2.

35 Figure 4 is a top plan view of the table top.

Figure 5 is a detail perspective view of the head member.

Figure 6 is a fragmentary perspective view 40 of the upper end of the pedestal, showing the saddle and bearings.

Figure 7 is a sectional view taken approximately on the line 7—7 of Figure 3.

Figure 8 is a perspective view of the table 45 top, and

Figure 9 is a similar view of the circular disc.

In the drawings when for the purpose of 50 illustration is shown the preferred embodiment of my invention, the numeral 1 design-

nates generally the stationary base, the same comprising a pair of parallel spaced bars 2 and 3 respectively, which are interconnected at their intermediate portion by the cross bar 4. These parallel spaced bars are formed 55 with longitudinally extending grooves in their inner opposed faces as illustrated at 5 and 6 to provide guide means for receiving the longitudinal side edge portions of the auxiliary base or platform 7 which is slidable 60 on the main base 1.

A depending lug 8 is formed on the bottom of this slidable platform 7 adjacent one end thereof and this lug is formed with a vertical slot which extends upwardly thereof in the 65 manner as is more clearly disclosed in Fig. 3. An elongated threaded rod 9 is threaded through a threaded bore 10 formed in the central portion of the cross bar 4 which bridges the spaced side bars 2 and 3 of the 70 main base 1 and the outer end of this rod extends through the lug 8 which depends from one end of the platform 7 and secured on the outer end of this rod is an actuating handle 11. A collar 12 is disposed within 75 the slot formed within the depending lug 8 and this collar is secured on the portion of the rod 9 which extends through the slot. This construction provides a means whereby the platform 7 may be moved longitudinally 80 along the main base 1 when the handle or crank 11 is actuated.

Extending upwardly from this auxiliary base or platform 7 is the substantially rectangular hollow pedestal or standard 13 and 85 the upper end of this pedestal is cut away at one pair of opposed sides and formed on the opposite pair of opposed sides are the bearings 14. The purpose of these bearings 14 will be hereinafter more fully described. 90

Extending laterally from the edges of the sides of the rectangular shaped pedestal in which the ears 14 are formed are the plate-like projections 15, the upper edges of these plate-like projections being connected together as at 16 and this construction provides what I term as a saddle, the same being designated generally by the numeral 17. 95

The present invention further includes the provision of a block-shaped head 18 100

- which is disposed between the bearing carrying sides of the pedestal 13 at the upper end thereof and this head member is formed with the laterally projecting arms 19 and 20, the upper faces of which lie flush with the upper face of the head in the manner as is more clearly disclosed in Figure 3 of the drawings. A pair of trunnions 21 are secured on the opposite sides of the head 18 by any appropriate fastening means and these trunnions are disposed within the respective bearings 14 whereby said head is adapted for vertical swinging movement in the upper end portion of the pedestal or standard 13.
- 15 Suitable plates 22 are disposed on the securing bolts 23 associated with the head 18 and the trunnions 21 and these plates engage the outer faces of the bearings in the manner clearly illustrated in Figure 2.
- 20 The manner in which the head member 18 and the laterally extending arms 19 and 20 carried thereby are actuated for disposing the head in various tilted positions will be presently described.
- 25 An enlarged circular disc 24 is disposed on top of the head 18 and its laterally projecting arms 19 and 20 respectively, and this disc is further adapted for rotation on said head member through the medium of the bolts 25 which extend centrally through the head and through the disc as shown in Figure 3. This disc is formed with an annular groove in its outer peripheral edge as indicated at 26 and cooperating therewith is the inner end of the threaded bolt 27 which is threaded through an upstanding ear 28 formed on the outer end of the laterally projecting arm; a suitable handle or lever 29 being associated with the headed end of the bolt for actuating the same. This construction provides a means whereby the disc 24 may be locked against rotation on the head member 18.
- Secured on the upper face of this rotatable disc 24 are the parallel spaced guide members 30 and cooperating with which are the guide strips 31 secured on the bottom faces of the complementary sections 32 and 33 of the table top 34. This table top is also circular in design and the complementary sections are substantially semi-circular. Each of the complementary sections of the table top is formed with a series of elongated inverted T-shaped slots 35 as is clearly shown in Figures 1 and 3 of the drawings and the same provides a means for receiving the heads of bolts to which the work which is to be supported on the drill press table is secured in the manner well known in the art and when the heads of the bolts are disposed within certain of these inverted T-shaped slots the work will be properly supported on the table top.
- The complementary sections 32 and 33 of the circular table top 34 in addition to pro-

viding a table top when closed, further cooperate to provide a vise, the inner opposed edges of the semi-circular sections being adapted to grip and secure the work and for the purpose of actuating the complementary sections so that the same may be moved away or toward each other, I have provided a pair of threaded rods 36 and 37 respectively. These rods are threaded in right and left hand directions respectively and the same are threaded through suitable threaded lugs 38 provided therefor on the upper face of the circular disc 24 in the manner as is clearly illustrated in Figures 2 and 3 of the drawings.

A depending lug 39 is formed on the bottom face of the complementary semi-circular section 32, the outer edge thereof through which extends the unthreaded outer end of the rod 36. A similar lug 40 is formed on the bottom face of the other complementary semi-circular section 33 of the circular table top 34 adjacent its outer edge and the unthreaded outer end of the threaded rod 37 extends through this lug. Each of the last mentioned lugs are formed with a vertical slot to accommodate the collar 41 which is secured on the respective threaded rod and it is readily obvious that when the outer ends of the threaded rods 36 and 37 are rotated in one direction, the complementary sections 32 and 33 will be moved inwardly or outwardly depending upon the direction in which the rods are turned so that the inner opposed edges of the complementary sections may be moved inwardly toward each other or outwardly away from one another to provide a vise. The circular table top 34 which includes the semi-circular complementary sections 32 and 33 will swing with the head member 18 as a unit during the tilting of the table top in the manner which will now be specifically described and furthermore the circular table top will also be adapted to rotate simultaneously with the rotation of the circular disc 24 when the locking bolt 27 is disengaged from the grooved peripheral edge of the disc.

Adapted for vertical reciprocatory movement within the hollow pedestal or standard 13 is the block 42. This block is formed in one pair of opposed sides with vertical grooves for cooperation with the vertically extending ribs 43 provided on the adjacent sides of the hollow pedestal whereby the block will be guided during its vertical sliding movement within the pedestal.

The slideable block 42 is operatively connected to the head member 18 through the medium of the link 44 which is pivotally secured at its upper end to a depending gear 45 formed on the bottom of the laterally extending arm 20 adjacent the head 18 as illustrated at 46. The lower end of this link is pivotally connected to an upstanding gear 47.

formed on the upper face of the block 42 and the pivotal connection between the lower end of the link and this gear is shown at 48.

The means for raising and lowering the block 42 comprises a lug 49 which projects from one side of the block 42 through the adjacent side of the rectangular shaped side of the pedestal 13, said side of the pedestal being formed with the cut-out portion 50 to accommodate this lug in the manner as clearly illustrated in Figure 1. This lug is formed with a vertical threaded bore through which extends the threaded shaft 51. The lower end of this shaft is supported in any appropriate manner on the auxiliary base or platform 7 and secured on the upper end of this shaft is a bevel gear 52 which meshes with a bevel gear 53 secured on a stub shaft 54 which is supported on the upper portion of the pedestal 13 by the supporting bracket 55. A suitable crank 56 is secured on the outer end of this stub shaft 54 for actuating the same.

Manifestly by rotating the shaft 51 in one direction, the threaded lug 49 will move upwardly on the shaft and simultaneously will cause the block 42 to slide upwardly in the hollow pedestal and during this upward movement, the link 44 will move upwardly, causing the vertically swinging head member 18 to be raised and when the arm 19 strikes the bridge portion 16 of the saddle 17, the head member and the circular table top carried thereby will be lifted in its upward swinging movement so that said table top will be disposed in a substantially horizontal position.

Obviously by rotating shaft 51 in the reverse direction, the block 42 will move downwardly in the hollow pedestal 13 and the link 44 will in turn cause the head member 18 to swing on its pivot so that the table top 34 will be tilted to any angular position and for the purpose of securing the table top in any predetermined tilted position, I provide a slotted arm 57 which is pivotally secured at its upper end to the outer end portion of the laterally projecting arm 20 associated with the pivoted head 18 and cooperating with the lower free end of this slotted arm is the bolt 58 which extends through the adjacent side of the pedestal and this bolt and slotted arm is clearly disclosed in Figure 3. A thumb nut 59 is threaded on the outer threaded end of the bolt 58 for tightening the same so that the slotted arm cannot move downwardly and this will provide a positive and efficient means for securing the head member 18 and the table top carried thereby in any predetermined tilted position.

It will thus be seen from the foregoing description, that I have provided a drill press table which is capable of being adjusted to various positions so that the work can be properly supported in any desired angle or place with respect to the drilling implement.

Furthermore the simplicity in which my device is constructed enables the parts to be readily and easily adjusted and a device of this character will at all times be strong and durable.

While I have shown the preferred embodiment of my invention, it is to be understood that various changes in the size, shape and arrangement of parts may be resorted to without departing from the spirit or sacrificing any of the advantages of the appended claim.

What I claim is:

In a drill press table, a base, a pedestal extending upwardly therefrom, a pair of vertically disposed and spaced plates, an offset at the upper end of the said plates, the cross member connecting said plates at the extremities of said offset, a slide block between said plates, means for moving said blocks vertically, an elongated block, an arm pivoted at one end to one of the vertical plates, and at its opposite end to one end of said elongated block, the opposite ends of said elongated plates being adapted to rest upon said cross member when disposed in horizontal plane, a pivotal link connection between said elongated block and said slide block, and a table top for disposition upon said elongated block.

In testimony whereof I affix my signature.

ROBERT E. STUBBS.
